UNITED STATES PATENT OFFICE.

EVERETTE A. BURMESTER, OF DETROIT, MICHIGAN.

WRINGER.

1,323,348.

Specification of Letters Patent.

Patented Dec. 2, 1919.

Application filed December 23, 1918. Serial No. 267,898.

To all whom it may concern:

Be it known that I, EVERETTE A. BURMESTER, a citizen of the United States, residing at Detroit, county of Wayne, State of Michigan, have invented a certain new and useful Improvement in Wringers, and declare the following to be a full, clear, and exact description of the same, such as will enable others skilled in the art to which it 10 pertains to make and use the same, reference being had to the accompanying drawings, which form a part of this specification.

My invention relates to wringers and an object of my improvements is to obviate the 15 breaking and displacement of buttons from garments subjected to their action.

I accomplish this object in the device illustrated in the accompanying drawings in which:

20 Figure 1 is an elevation of a wringer embodying my invention.

Fig. 2 is a section on the line 2—2 of Fig. 1.

Fig. 3 is a detail sectional view of the 25 end of one of the rollers.

Fig. 4 is an elevation partly in section of a portion of a wringer embodying a modified form of my invention.

Fig. 5 is a detail sectional view illustrating a detail of construction.

a a is the frame of a wringer and b b are the rollers, c c² c³ c⁴ are the gear wheels by which the rollers b b are geared together.

In the form shown in Figs. 1, 2 and 3 the 35 rollers b b are of the ordinary construction for the greater portion of their length but peripheral covering which is slightly elastic is replaced at one end of each of said rollers by a band b⁴ of considerable elasticity and 40 to secure this greater elasticity it is made of thicker and softer rubber and preferably provided with an annular air space b^{4a} inside of its integral periphery. Either one or both of the rollers may be provided with 45 the band b⁴ and when both are so provided it is at adjacent ends, as indicated in Fig. 1.

d is a plate secured in a guide e upon one of the uprights of the frame a and adapted to slide in the direction of the axes of the 50 rollers b b in said guide. Such guide may be a strip of metal secured at its ends to the frame and passing over the plate d and having a slot e² therein, the plate d being provided with a pin e³ extending through said 55 slot. d² is a latch upon the plate d having

a tooth d³ adapted to engage in an aperture e⁴ in the guide e when said plate is in its inner position. The plate d is of such a size that when pushed to its inner position, as shown in Fig. 2, it will form a shield extending in front of the portion of the rollers b b on which are the bands b⁴ b⁴ as indicated in Fig. 2.

When a garment having buttons that are apt to be broken is to be passed through between the rollers b b the plate d is withdrawn to the position shown in Fig. 1 and the portion of the garment having the buttons thereon is caused to pass between the soft bands b⁴ b⁴ which yield to the button as it passes through between them without breaking or displacing the same as indicated in Fig. 4.

When the wringer is to be used with materials that have no buttons upon them the plate d is moved to its inner position and held therein by the latch d² so that the bands b⁴ b⁴ are guarded and the garments only pass between the usual surface of the rollers b b.

As a modified form of the above construction one of the rollers b b may be constructed so that it may move in the direction of its axis, its shaft b² sliding through the gear wheel c² or c⁴ and through its bearings, a pin b⁶ engaging in a slot b⁵ to permit such movement. The shaft b² may be provided at one end with an annular peripheral grooves b³ b³ in which a pawl f (Fig. 5) actuated by a spring f² may engage to hold 90 the roller in one or the other position. In this case the sides of the frame a are cut out as shown at a² and a³ so that when the movable roller is moved to its farthest position to the left, as shown in Fig. 4 the soft band b⁴ will be incased in the hollow a² of the frame. In this position the wringer presents only the ordinary surface of the two rollers. As an alternative position the movable roller may be moved to its right hand position as shown in Fig. 4 in which its right hand end will extend into a cavity a³ in the side of the frame and the soft band b⁴ will be exposed and may be used as above described.

105 What I claim is:

1. In a wringer, the combination of a roller, a flexible peripheral covering therefor, a portion of the covering at one end of said roller being more elastic than the 110

covering of the remainder of said covering, substantially as and for the purpose described.

- 5 2. In a wringer the combination with a roller having a portion of its periphery more yielding than the remainder thereof, of means for shielding said portion of said periphery and removing said shielding means at will.
- 10 3. In a wringer the combination with a roller having a portion of its periphery

more yielding than the remainder thereof, a casing formed in the frame of said wringer adapted to receive the yielding portion of said roller, said roller being movable longitudinally to pass into said cavity and be removed therefrom, said casing being adapted to form a shielding means for the part of the roller therein. 15

In testimony whereof, I sign this specification. 20

EVERETTE A. BURMESTER.
